UNITED STATES PATENT OFFICE.

REINHOLD HERMAN, OF PITTSBURGH, PENNSYLVANIA.

ADJUSTABLE DISPLAY DEVICE.

1,290,189.

Specification of Letters Patent.

Patented Jan. 7, 1919.

Application filed September 24, 1917. Serial No. 192,930.

To all whom it may concern:

Be it known that I, REINHOLD HERMAN, a citizen of the United States, residing at Pittsburgh, in the county of Allegheny and State of Pennsylvania, have invented certain new and useful Improvements in Adjustable Display Devices, of which the following is a specification.

This invention relates to certain new and useful improvements in adjustable display devices.

The primary object of the invention is the provision of a holder for a plurality of display packages such as the well known cake and cracker boxes whereby the latter are readily positioned for extracting the contents thereof when it is desired to make a sale.

A further object of the invention is the provision of a display holder for boxes that possesses great strength and durability but is easy and inexpensive to manufacture while the same possesses expansive qualities and may be arranged in a plurality of separable sections or units readily combined for accommodating the number of boxes desired.

A still further object of the invention is the provision of a holder or stand arranged with a bodily movable support for articles containing boxes, the said supports being slidably shiftably arranged for suitably positioning the boxes for opening the same and at which times the support is in a retained inclined forward position.

With these general objects in view and others that will appear as the nature of the invention is better understood, the same consists in the novel construction, combination and arrangement of parts hereinafter more fully described, illustrated in the accompanying drawings, and pointed out in the appended claims.

In the drawings forming a part of this application and in which like designating characters refer to corresponding parts throughout the several views:—

Figure 1 is a front elevation of the device showing the lower tray thereof provided with display boxes,

Fig. 2 is a side elevation of the device, empty and partly broken away,

Fig. 3 is a perspective view of a partition rail provided for the trays,

Fig. 4 is a perspective view of a side rail of a tray,

Fig. 5 is a perspective view of an end

portion of one of the side sections of the base of the device, parts being broken away,

Fig. 6 is a side elevation of a portion of one of the trays with a box arranged therein and with parts broken away.

Fig. 7 is a vertical transverse sectional view taken through a side portion of the tray and the adjacent side bar of the frame, and

Fig. 8 is a longitudinal sectional view through a tray having a box positioned therein, parts being broken away.

It being understood that the device is arranged for holding a plurality of boxes containing commodities for vending, the form of the device herein shown for purposes of illustration, arranges two boxes 10 of the common form of cracker boxes, arranged within one of three supporting trays 11 carried by the metal frame 12.

The frame 12 consists of a base 13 having opposite side sections 19 arranged with forwardly and rearwardly curved supporting legs 14 and 15 at the opposite ends thereof while channel bars 16 are secured between the pairs of front and rear legs arranged overlying beveled blocks 17 carried by the said legs, bolts 18 being provided for securing the channel bars to the blocks.

The structure so far described forms a rectangular base with the channel bars 16 forming the front and rear portions thereof and the spanning members 20 of the side sections 19 forming the opposite sides of the base. Corner posts 21 preferably formed of channel bars are arranged upright attached adjacent the opposite ends of the side sections 19 by means of bolts 22 secured through the posts 21 and upright plates 23 carried by the opposite ends of the spanning members 20. A rectangular frame 34 is arranged at the top of the device secured to the upper free ends of the corner posts 21.

The spanning members 20 of the side sections 19 of the base are adapted for mounting a shiftable tray 11 thereon while similar spanning sections 20' are arranged between the front and rear post 21 of the frame 12 at points above the base 13 adapted for supporting superposed trays in a similar manner. Each of the trays 11 is formed of the spaced side rails 25 having similar front and rear ends 26 formed of channel bars fitting over inwardly projecting ears 27 arranged at the opposite ends of the side rails 25 and

secured to said ears by means of bolts 28. A partition rail 29 is centrally provided for each tray 11 having a depending attaching plate 30 adjacent its opposite ends for engaging the inner sides of the ends 26 of the trays and secured in position by means of bolts 31. The partition rails 29 have spaced longitudinal flanges 32 upon their upper sides as well as upturned end flanges 33, the latter lying flush with the outer faces of the ends 26 while the cracker boxes 10 are seated within the tray upon the opposite base flanges 34 of the partition rail 29 and upon the inner upper flanges 35 of the side rails 25. 15 A rectangular plate 36 is arranged at each end of each side rail 25 forming the corners of the trays when taken with the upstanding web 37 centrally arranged longitudinally of each of the side rails. 20 The tray supports 20' are arranged with end plates 38 similar to the plates 23 and adapted for fitting within the corner post 21 with the members 20' secured thereto by bolts 39. A roller 40 is journaled upon a 25 boss 41 at the rear outer corner of each of the side rails 25 adapted for traveling upon the adjacent inner base flange 42 of the adjacent supporting section 20 or 20' which is of the general form of an I-beam. Grooved 30 wheels 43 are journaled upon brackets 44 depending from the supporting sections 20 and 20' adjacent the forward ends thereof and arranged inwardly of the said sections, whereby the depending central rib 45 of the 35 adjacent side rail 25 of the tray 11 is positioned thereon. In this manner it will be seen that the trays 11 will be free to slide inwardly and outwardly of the frame 12 upon the rear rollers 40 of the trays and 40 upon the forward wheels 43 of the side sections 20 and 20' of the frame.

The rollers 40 being adapted to travel upon the base flanges 42 of the side sections 20, 20' of the frame 12, are limited in their forward movement thereon by means of curved stops 46 arranged between the top and bottom flanges of the said sections at points slightly spaced from the front of the frame 12 and thereby permitting the trays 11 to be slidably moved forwardly by pulling upon the handles 47 of the trays, the trays being prevented from removal from the frame by the engagement of the rollers 40 with the stops 46. The mounting ribs 45 of the side rails 25 are arranged with a curved portion or notch 48 spaced from the rear ends of the side rails a distance substantially equal to that between the stops 46 and wheels 43 of the side sections 20, 20' 55 so that upon the trays being withdrawn sufficiently to engage the roller 40 with stop 46, the notch 48 will engage the wheels 43 positioning the trays 11 in a forwardly inclined arrangement with the boxes 10 readily accessible for opening the lids 49 thereof.

The partition rails 29 are preferably arranged with longitudinal slots 50 between the ribs 32 thereof while the side rails 25 are longitudinally slotted as at 51 and the side members, 20, 20' as at 52 for the purpose of lightness as well as affording ample ventilation for the entire device. The webs 53 of the side supports 20' are cut away at their opposite ends as at 54 for accommodating the inner ends of the bolts 39 and their lock nuts 55.

A serviceable holder for different forms of boxes is arranged whereby a large number of boxes are arranged for display purposes in compact arrangement and permitting access thereto whenever found desirable. It will be understood that a larger or smaller number of trays 11 may be accommodated in the frame 12 by changing the number of pairs of supporting sides 20', for instance by providing a larger number of trays when the boxes 10 are of less height than that herein indicated. The device has the further expandable feature of being adapted for attachment to an adjacent similar frame by means of the projecting ends 56 of the front and rear frame bars 16. It will be understood that casters 57 are preferably arranged for the legs 14 and 15 for readily changing the position of the entire device.

What I claim as new is:—

1. A display stand including a base formed of opposite side sections each arranged with legs and a supporting spanning member, transverse blocks carried by the said legs, forwardly and rearwardly positioned channel bars secured over the said blocks, and a tray slidably mounted upon the said spanning members adapted for downward inclination when projected.

2. A display stand including a base formed of opposite side sections each arranged with legs and a supporting spanning member, transverse blocks carried by the said legs, forwardly and rearwardly positioned channel bars secured over the said blocks, upright plates carried by the opposite ends of the spanning members, corner posts for the device of channel bar formation secured upright to the said plates, opposite side members arranged between the said posts similar to the said spanning members, and trays anti-frictionally mounted upon the said side members and spanning members adapted for projecting downwardly of the device when the trays are in their open position.

3. A display stand comprising a base having spanning side supports of I-beam formation, wheels carried in journaled relation adjacent the forward ends of said supports, a box-holding tray formed with side rails having depending ribs mounted for travel upon the said wheels, rollers upon the said side rails mounted for travel upon the lower inner base flanges of the said side supports,

stops upon the inner side of said supports spaced from the forward ends thereof between the top and bottom flanges of the supports arranged within the path of movement of the said rollers adapted for limiting the forward movement of the tray, the ribs of said side rails having notches therein adapted for the reception of the said wheels when the rollers are in engagement 10 with the said stops with the tray in its open forwardly inclined engagement.

4. A display stand comprising a base having spanning side supports of I-beam formation, wheels carried in journaled relation 15 adjacent the forward ends of said supports, a box-holding tray formed with side rails having depending ribs mounted for travel upon the said wheels, rollers upon the said side rails mounted for travel upon the lower 20 inner base flanges of the said side supports, a partition rail for the tray having end plates lying flush with the front and rear sides of the tray and having opposite bottom flanges with spaced longitudinal up- 25 standing ribs adjacent the inner ends of the flanges, the said side rails having inwardly projecting flanges in the same plane as the flanges of the partition rail adapted for the mounting reception of boxes thereon between the said partition rail and 30 side rails.

5. A display stand comprising a base having spanning side supports of I-beam formation, wheels carried in journaled relation adjacent the forward ends of said supports, 35 a box-holding tray formed with side walls having depending ribs mounted for travel upon the said wheels, rollers upon the said side rails mounted for travel upon the lower inner base flanges of the said side supports, 40 stops upon the inner side of said supports spaced from the forward ends thereof between the top and bottom flanges of the supports arranged within the path of movement of the said rollers adapted for limiting 45 the forward movement of the tray, the ribs of said side rails having notches therein adapted for the reception of the said wheels

when the rollers are in engagement with the said tops with the tray in its open forwardly inclined engagement, a partition rail for the 50 tray having end plates lying flush with the front and rear sides of the tray and having opposite bottom flanges with spaced longitudinal upstanding ribs adjacent the inner ends of the flanges, the said side rails having inwardly projecting flanges in the same plane as the flanges of the partition rail adapted for the mounting reception of boxes thereon between the said partition rail and 55 side rails.

6. A tray comprising side rails having inwardly projecting longitudinal supporting flanges and attaching ears at the ends of said flanges, channel bars secured over the said ears connecting the rails together in 65 rectangular formation, a partition rail spanning said channel bars having depending end plates secured thereto with the bottom of the partition rail in the same plane as the said flanges of the side rails adapted 70 for the supporting reception of boxes thereon, upstanding end members upon the said partition rail and spaced ribs longitudinally arranged upon the bottom of the partition rail between the said ends thereof.

7. A display stand including a frame having grooved rollers journaled thereon, a tray slidably mounted on said frame, said tray having depending side flanges movable and guided in the grooves of said rollers to 80 prevent sidewise movement of the tray, said flanges being notched to receive said rollers and thereby retain the tray in a downwardly inclined position when opened.

8. A display stand including a frame having rollers journaled thereon, and a tray slidably mounted on said frame, said tray including side members movable on said rollers, said side members being notched to receive said rollers and thereby retain the 90 tray in a downwardly inclined position when open.

In testimony whereof I affix my signature.
REINHOLD HERMAN.
